RETAINING WALL

Albert Henderson, Pittsburgh, Pa., assignor to
William P. Witherow, Pittsburgh, Pa.

Application April 22, 1939, Serial No. 269,471

3 Claims. (Cl. 61—39)

This invention relates to a retaining wall and, in particular, to a wall composed principally of precast members of concrete or the like, having standard dimensions, which can be made up at 5 a centrally located plant and assembled on the job by relatively unskilled labor.

Numerous forms of retaining walls have been suggested heretofore but have all been subject to the objection that numerous elements of 10 special shape were required and the limitations imposed with respect to the possibility of designing walls of any desired height. It is an object of my invention therefore to improve generally upon the construction of retaining walls known heretofore and particularly to provide a wall 15 composed of relatively inexpensive elements which can be quickly assembled to form a wall.

In a preferred form, my invention comprises a plurality of substantially vertical members extending upwardly from a supporting foundation or footing and adapted to be loaded as beams. Said members are laterally braced and a plurality of precast plank-like members of concrete or the like are disposed against the inner edges 20 of the beams to form a wall surface. The beams and braces may be embedded in a poured foundation of concrete or the like while the latter is still plastic or may be supported on top of suitable footings, in which case the lower ends of the 25 beams and braces are tied together by short horizontal members, forming triangular structures or A-frames. A preferred embodiment of the invention and a modification thereof are illustrated in the accompanying drawings. In the 30 drawings

Fig. 1 is an elevation of a retaining wall embodying the invention;

Fig. 2 is a sectional view taken substantially along the line II—II of Fig. 1;

Fig. 3 is a plan view;

Fig. 4 is a sectional view taken substantially along the line IV—IV of Fig. 2;

Fig. 5 is a partial sectional view taken substantially along the line V—V of Fig. 2;

Fig. 6 is a view similar to Fig. 2 showing a 45 modification;

Fig. 7 is a plan view thereof, partly broken away; and

Fig. 8 is a partial elevation thereof.

Referring now in detail to the drawings, and for the present to Figs. 1 through 5, the preferred form of the invention comprises a foundation or footing 10 of concrete or the like poured in place. While the poured concrete is still 50 plastic, I erect substantially vertical members 11

and embed their lower ends in the foundation 10. The members 11 may conveniently be precast concrete planks and are preferably arranged in pairs, with a filler plank 11a therebetween, as shown in the drawings. The members 11 are 5 adapted to be loaded as beams and are connected together at their lower ends by pins 12 extending through holes formed therein. The pins 12 also serve as anchors to hold the beams firmly embedded in the footing. The beams 11 have 10 reinforcing incorporated therein as indicated at 13.

Bracing members 14 also have their lower ends embedded in the foundation 10. The upper ends of the braces 14 extend between the beams 11 of 15 each of the spaced pairs thereof as shown in Figs. 1 and 3. Pins 15 extend through aligned holes in the upper ends of the beams 11 and braces 14 to tie the latter firmly together. The braces 14 like the beams 11, are preferably precast concrete 20 planks or the like which may be made up to standard dimensions at relatively low cost. Pins 16 extending transversely through the braces 14 at their lower ends provide an anchorage for the latter in the footing 10 and this may be made 25 even more secure by disposing reinforcing mesh 17 on each side of the braces 14 above the pins 16. The footing may also be reinforced as at 18 to provide greater resistance to the downward load 30 on the wall. The beams and braces may be placed before instead of after the pouring of the footing if desired. Instead of a single brace for each set of beams, as shown, I may use a greater number and may either dispose all at the same angle or, in case of a wall of considerable height, 35 may use braces of different lengths disposed at different angles, in cooperation with each set of beams.

Additional pins 19 extend through aligned holes in the beams 11 and filler planks 11a. As shown 40 in Fig. 4, the pins 15 and 19 are shorter than the sum of the thicknesses of the beams 11 and the associated brace 14. The ends of the holes through which the pins extend are covered with grout as at 20 to prevent removal of the pins. 45

When the beams 11 and braces 14 have been erected and the foundation has set, stretchers 21 may be laid up on the latter between adjacent pairs of beams 11, the ends of the stretchers engaging the inner edges of the beams 11 as shown 50 in Fig. 5. The stretchers 21 are similar to the beams and braces in that they are preferably precast reinforced concrete planks made up to suitable standard sizes and lengths. As shown in Fig. 2, various sizes of planks may be employed, 55

depending upon the horizontal load at various heights above the foundation. The stretchers 21 are shown as laid on their sides but may also be laid on edge depending on the character of the earth to be retained and the span between adjacent pairs of beams 11.

After the stretchers 21 have been laid up as shown, the wall is ready for its fill. As clearly appears in Fig. 2, the weight of the fill holds the footing 10 against tilting and the horizontal load of the fill is transferred directly to the footing by the beams 11 and braces 14. The foundation 10 provides a continuous surface or deck to receive the weight of the fill. As an example of the economies which may be effected with the construction shown, the same standard precast plank may serve as beams 11, braces 14 and stretchers 21. These planks are supplied in standard lengths whereby a wall of almost any desired 20 type may readily be provided at low cost.

Figs. 6 through 8 illustrate a slightly modified form of wall in which separate foundations 25 are spaced along the length of the wall in contrast to the footing 10 which, as shown, preferably 25 extends continuously along the wall. An A-frame or triangle 26 is disposed on each footing 25. It includes a pair of vertical beams 27, a brace 28, a filler 28a, and base members 29, all composed of reinforced precast planks of suitable lengths 30 and connected together by pins 30. As shown in Fig. 7, the beams 27 are arranged in pairs with a brace 28 and filler 28a between them, while the horizontal members 29 are disposed outside the beams 27. Spacer planks 31 are shown between the braces 28 and the horizontal or base members 29.

Stretchers 32 are laid up between the adjacent A-frames 26. A course of stretchers is laid on the horizontal or base members 29, the stretchers 40 being precast planks disposed on edge, forming a substantially continuous deck between adjacent foundations. Additional stretchers are built up against the inner edges of the beams 27, as in the case of the wall shown in Figs. 1 through 5.

It will be apparent that the wall of Figs. 6 through 8 performs the same function as that shown in Figs. 1 through 5, the principal difference being that the overturning moment exerted on the former is resisted by the weight of the earth above the stretchers 32 disposed on the base members 29. If the pins 30 are not grouted in, they may be removed to permit knocking down the entire structure. Galvanized bolts may also be used instead of pins, for this purpose.

If a water-tight wall is desired, gasket strips of asphaltic felt or the like may be laid between adjacent stretchers. It will be understood, of course, that the length of the precast planks used as stretchers determines the spacing between

adjacent pairs of vertical beams. These stretchers are laid with mortar therebetween. Weep-holes may be provided by leaving spaces in the mortar joints between the stretchers near the bottom of the wall.

It will immediately be recognized that the structures shown in the drawings and described in detail above provide retaining walls which can be quickly erected from standard precast elements at low cost. The precast planks can be manufactured cheaply in quantity and can easily be assembled by unskilled labor. The construction of the wall is such, furthermore, that it can easily be designed to withstand almost any given horizontal thrust or overturning moment.

Although I have disclosed herein but a preferred form of the invention and a modification, it will be understood that changes in the structures shown and described may be made without departing from the spirit of the invention or the scope of the appended claims.

I claim:

1. A retaining wall comprising a monolithic, field-cast foundation slab, precast posts embedded in said slab in spaced relation adjacent one side 25 thereof, precast braces embedded in the slab adjacent the other side thereof, substantially in alignment with said posts, said braces extending toward the posts and being secured thereto, and precast stretcher units laid up on said foundation 30 behind said posts and extending between adjacent posts, whereby the entire weight of fill above said slab and behind the wall resists the overturning moment applied to said wall.

2. A retaining wall comprising spaced precast 35 posts, precast braces secured to said posts and extending downwardly therefrom, precast stretcher units laid up behind said posts and extending between adjacent posts, a substantially continuous horizontal deck between the posts and braces, 40 the posts and braces being secured to said deck, said deck being effective by the weight of fill thereabove, to resist the overturning moment applied to said wall.

3. In a retaining wall, a poured foundation, 45 precast beams extending upwardly from said foundation and having their lower ends embedded therein, precast stretchers extending between said precast beams defining the face of said wall, and precast braces connected to said precast 50 beams, extending downwardly and laterally therefrom, and having their lower ends embedded in said foundation, said foundation comprising a wide slab along the wall face providing a continuous deck adapted to receive fill thereabove 55 and effective by the weight of said fill to oppose the overturning moment applied to the wall.

ALBERT HENDERSON.
